ROSE PLANT

Svend Poulsen, Kelleris, Kvistgaard, Denmark, assignor to The Conard-Pyle Company, West Grove, Pa., a corporation of Pennsylvania

Application June 10, 1959, Serial No. 819,521

1 Claim. (Cl. 47—61)

2

Quantity of bloom: Abundant, both outdoors and in greenhouse.

Continuity: Continuous.

Fragrance: Slight. Nature—spicy.

5 Bud:

Peduncle.—Medium length; medium caliper; erect; rough; with numerous red hairs. Color—Garnet Brown, Plate 00918/1.

Before calyx breaks.—Size—small. Form—short; ovoid; with a conspicuous neck; with foliaceous appendages on the surface of the bud; with slender, entire foliaceous parts extending beyond the tip of the bud equal to $\frac{1}{4}$ or more of its length.

As calyx breaks.—Color—Vermilion, Plate 18/1.

As first petal opens.—Size—small. Form—ovoid. Color: outside—Blood Red, Plate 820, often mottled with Mimosa Yellow, Plate 602; inside—Aureolin, Plate 3 over basal half of petal, becoming blotched with Jasper Red, Plate 018.

Opening.—Opens up well.

20 Bloom:

Size (when fully open).—Small; from 2 inches to $2\frac{1}{4}$ inches.

Petalage.—Double; from 20 to 35 petals; arranged regularly.

Form.—Full at first, but becoming cupped; petals being at first loosely rolled outward, and remaining loosely rolled outward at maturity.

Petals: Leathery; with inside satiny and outside shiny.

Shape: Outer petals—obovate; intermediate petals—obovate; inner petals—obovate, and often irregular.

This description of a newly-opened flower was made from a rose grown outdoors in the month of September at West Grove, Pennsylvania, U.S.A.

35 *Color.*—Outer petal: outside surface—Cardinal Red, Plate 822, with basal quarter of petal often becoming Chrome Yellow, Plate 605/1; inside surface—Cardinal Red, Plate 822, at apex where first exposed to light, grading to Poppy Red, Plate 16/1, with basal half of petal Mimosa Yellow, Plate 602. Intermediate petal: outside surface—Jasper Red, Plate 018/1, over apical half of petal, and Chrome Yellow, Plate 605/1, over basal half; inside surface—Mimosa Yellow, Plate 602, changing abruptly to Poppy Red, Plate 16/1, where exposed to light. Inner petal: outside surface—Chrome Yellow, Plate 605/1, often blotched at apex with Jasper Red, Plate 018/1; inside surface—Aureolin, Plate 3/1, often with a narrow margin of Poppy Red, Plate 16/1, at apex.

40 This description was made from a rose that was open for 3 days outdoors in the month of September at West Grove, Pennsylvania, U.S.A.:

45 *Color.*—Outer petal: outside surface—Primrose Yellow, Plate 601/2 at base petal, becoming overlaid with Delft Rose, Plate 020; inside surface—Mimosa Yellow, Plate 602/3, changing abruptly to Turkey Red, Plate 721 where exposed to direct light. Inner petal: outside surface—Primrose Yellow, Plate 601/2 at base of petal, becoming lightly overcast with Delft Rose, Plate 020/2; inside surface—Turkey Red, Plate 721, grading to Mimosa Yellow, Plate 602/3.

50 *General color effect.*—Newly opened flower—Poppy Red, Plate 16/1, with center of bloom Aureolin, Plate 3/1. 3 days open—Turkey Red, Plate 721.

55 *Behavior.*—Drop off cleanly but slowly; main color changes with age to Carmine, Plate 21.

60 *Flower longevity.*—On bush in garden—5 days in

Flower

Locality where grown and observed: West Grove, Pennsylvania, U.S.A.

65 Flowers borne: Several to stem; in regular rounded clusters; on stems of medium length and normal strength.

Propagation: Holds its distinguishing characteristics through succeeding propagations by budding.

September. Cut roses grown outdoors and kept at living room temperatures—6 days in September.

Reproductive organs

Stamens: Many; arranged regularly about pistils. 5
 Filaments: Most with anthers; medium length. Color—Lemon Yellow, Plate 4.
 Anthers: Color—Mimosa Yellow, Plate 602/2.
 Pollen: Moderate. Color—yellow.
 Pistils: Medium number.
 Styles: Uneven; medium length; medium caliper; bunched.
 Stigma: Color—yellow.
 Ovaries: All enclosed in receptacle.
 Hips: None observed.
 Sepals: Permanent; medium length; straight.
 Seeds: None observed.

Plant

Foliation:

Leaves.—Compound of 3 to 5 leaflets; abundant; medium size; leathery; glossy.
Leaflets.—Shape—oval, with apex acuminate. Base—obtuse. Margin—simply serrate.
Color.—Mature: upper surface—Spinach Green, Plate 0960; under surface—Willow Green, Plate 000862/1. Young: upper surface—Spinach Green, Plate 0960/1, margined with Garnet Brown, Plate 00918/3; under surface—Willow Green, Plate 000826/1, lightly overcast with Garnet Brown, Plate 00918/3, and with veins of Garnet Brown, Plate 00918/1.
Rachis (the supporting stem of the compound leaf).—Medium. Upper side—grooved; hairy. Under side—moderately hairy.

Stipules.—Medium length; narrow; with points of medium length turning out at an angle at 45°.
Disease resistance.—Quite resistant to both mildew and blackspot, as determined by comparison with other varieties grown under the same cultural conditions at West Grove, Pennsylvania, U.S.A.

Growth:

Habit.—Bushy; upright; much-branched.

Growth.—Free.

Canes.—Medium caliper.

Main stems.—Bright. Color—Spinach Green, Plate 0960/2. Prickles—several; color—Garnet Brown, Plate 00918/1. Hairs—none.

Branches.—Bright. Color—Spinach Green, Plate 0960/2. Prickles—several; color—Orange Buff, Plate 507, overlaid with Oxblood Red, Plate 00823/3. Hairs—none.

New shoots.—Dull. Color—Lettuce Green, Plate 861, overlaid with Oxblood Red, Plate 00823/3. Prickles—several; color—Oxblood Red, Plate 00823/3. Hairs—none.

I claim:

A new and distinct variety of rose plant of the hybrid polyantha class, substantially as herein shown and described, characterized particularly as to novelty by the unique combination of vigorous, erect and bushy habit of growth, leathery and glossy dark green foliage, an unusually good resistance to both blackspot and mildew, small, double and perfectly formed flowers, a leathery petal texture accompanied by unusually good keeping qualities of the blooms as cut flowers, and a distinctive Poppy Red general color tonality of the open flowers, sharply contrasting with an Aureolin center.
